UNITED STATES PATENT OFFICE.

AZEL AMES, JR., OF NEW YORK, N. Y., ASSIGNOR OF ONE-HALF TO ASBURY G. WILSON, OF WILKINSBURG, PENNSYLVANIA.

LIGHTNING-ARRESTER.

No. 866,556.

Specification of Letters Patent.

Patented Sept. 17, 1907.

Application filed August 16, 1906. Serial No. 330,780.

To all whom it may concern:

Be it known that I, AZEL AMES, Jr., a citizen of the United States, residing at New York city, in the county of New York and State of New York, have invented 5 new and useful Improvements in Lightning-Arresters, of which the following is a specification.

This invention relates to lightning arresters of the kick-coil type wherein a current of high voltage, such as lightning, sets up a magnetic field, the reacting tendency of which is to restrain the flow of current and cause it to jump to ground.

One object of the invention is to provide for so assembling the parts of the device as to avoid danger of a permanent ground, caused by the lodgment of foreign 15 matter between the coil and ground terminal, or by fusion, commonly known as "bugging".

Another object is to simplify the construction and provide a compact arrangement of the parts by combining the soft iron core and the ground terminal in one 20 part or element, which is of course located within the coil.

Still a further object is to provide means for variably spacing the combined core and ground terminal from that portion of the coil to which it is exposed, and 25 thereby predetermining the electromotive force at which a discharge or jump from the coil to the core will take place.

A further purpose is to provide open insulation of improved form between the coil and core.

30 These and other objects and advantages of the invention are fully described hereinafter, reference being had to the accompanying drawings, wherein

Figure 1 is a side elevation of the improved device. Fig. 2 is a sectional plan view, taken on line 2-2 of 35 Fig. 1, Fig. 3 is a vertical cross-sectional view on line 3-3 of Fig. 1, and Fig. 4 is a similar view of the frame and coil, with the core and interposed insulation removed. Figs. 5 and 6 are detail views of the core, and Figs. 7 and 8 are similar views of the mica insulation.

40 The frame of the device is formed of porcelain or other insulating material, and is constructed with the central or body portion 2, oval in cross section, and having base lugs or feet 3 for securing the device wherever required. Projecting from the top of the frame are

45 lugs 4 carrying binding device 5 and 6. Also, at one end of the frame is binding device 7 connected to device 6 by fuse 8. One of the circuit terminals is connected to device 5, and the other terminal may be connected either to device 6 or 7, depending on whether

50 or not the protection afforded by fuse 8 is desired. One face of body 2 is recessed at 9, the recess opening through an end of the frame as shown. The face of body 2 is grooved spirally and wound there-around is coarse wire 10, the extremities of which are secured, respectively, to binding devices 5 and 6. The grooved

face of body 2 holds the convolutions of coil 10 separated and insulated from each other. Copper wire is preferably used.

Within recess 9 is the combined core and ground terminal which, in the preferred construction, consists of a soft iron plate 11, which fits the back or rear part of recess 9, and the front or face plate 12 which bears flatly against plate 11. Plate 12 is formed of a suitable conducting material, carbon being preferably used. Extending from the outer end of plate 11 is ground wire 65 13. At the open side of the frame the core is spaced from coil 10, this space being the distance the current must jump to ground. Within this space is open insulation consisting, preferably, of a thin perforated sheet 14 of mica which bears against the carbon, and 70 between this sheet and the wire is the spacing element 15, also preferably mica. As the electromotive force required to jump a given air space bears a certain relation to the width of that space, the electromotive force at which a discharge or ground will take place may be 75 graduated or determined by the thickness of spacing element 15. In this way the device may be adjusted to meet different requirements or conditions. The combined core and ground terminal, together with the insulating and spacing elements, may be readily slipped 80 in and out through the open end of the frame, and thus the device may be cleaned and repaired without being removed from the circuit. After coil 10 is wound, it is sprung or depressed slightly into the open side of recess 9, as shown in Fig. 4, and bears inwardly against 85 the spacing element and core and holds them securely in place.

Plate 12 prevents fusion (commonly known as "bugging") between the metals of the core and coil, and thus prevents the formation of a permanent ground. 90 The perforated mica 14 affords sufficient open space between the core and the coil through which the current jumps when grounding, and at the same time forms a screen which prevents the lodgment of foreign matter, such as cinders, between the coil and core, 95 avoiding the ground connection which such matter thus lodged might otherwise produce.

The operation of devices of this character is well understood by those skilled in the art. When the circuit wire leading to the apparatus protected by the arrester becomes overcharged as when struck by lightning, a counter-electromotive force is set up owing to the presence of the soft iron of the core, which, in turn, tends to restrain or retard the flow of the current and causes it to jump from the coil to the combined ground terminal 105 and core and from thence to ground.

The advantages resulting from the invention reside in preventing premature grounding of the current, and in the simple and compact construction obtained by combining the ground terminal and the core.

While I have shown and described the preferred embodiment of the invention, the same may be varied in many ways without departing from the spirit and scope thereof as defined by the appended claims.

5 I claim:—

1. In a lightning arrester, the combination of a frame body of insulating material having a recess open at one side, wire coiled around the body and extending over the open side, and a combined core and ground terminal 10 within the body-recess and spaced from the coil.
2. In a lightning arrester, the combination of a frame body of insulating material open at one side, wire coiled around the body and extending over the open side, a combined core and ground terminal within the body-recess, 15 and open insulation between said face and the coil.
3. In a lightning arrester, the combination of a frame

of insulating material recessed, the recess being open at the end and at one side, wire coiled around the body and extending over the open side of the recess, and a combined core and ground terminal 20 slideable through the open end of the body-recess.

4. In a lightning arrester, the combination of a recessed body of insulating material open at one side, wire coiled around the body and extending over the recess, and a combined core and ground terminal within the body-recess and 25 held therein by the pressure of the coil.

In testimony whereof I have signed my name to this specification in the presence of two subscribing witnesses

AZEL AMES, JR.
